MINNESOTA.

METHOD OF CARRYING AND FEEDING SHEETS TO THE COLD ROLLS OF SHEET AND TIN PLATE MILLS.

Application filed November 30, 1923. Serial No. 677,746.

This invention relates to the cold rolling of tin plate and is directed to the provision of certain improvements whereby the output of a set of cold rolls is increased and as a consequence the power consumption, the labor cost and the capital investment incident to the cold rolling of tin plate are decreased.

Prior to this invention it has been the established practice for many years and is now the practice in the largest and best equipped tin plate mills, to introduce tin plates to the first of a series of stands of cold rolls manually, the operator picking the plates up successively and introducing the edge of each plate between the first pair of rolls. Of course care must be observed in so feeding the plates to the rolls; for instance, the rear edge of one plate must pass through the rolls before the forward edge of the next succeeding plate is introduced.

We have discovered that this practice which, as stated above, has been the accepted and established practice in the best plate mills for many years past, can be substantially improved so as to get substantially greater results or to produce the same results with less labor and a less investment in apparatus, by the simple expedient of employing in connection with the cold rolls a simple form of belt conveyor upon which the plates may be placed successively by hand and by which they would be carried to the rolls and introduced between them one after another.

In accordance with this practice, just as in connection with the prior established practice, the plates are picked up one after another by hand and placed in position by the operator by hand, but when the operation involves placing the sheets upon the conveyor belt in positions thereon set by suitable projections on the conveyor surface and the belt carries the plates to the cold rolls, the rate at which the plates are fed to the rolls is substantially greater than in the case where the manual operation is one of picking up the plates successively and introducing their forward edges between the rolls.

The plates may be more readily positioned upon the belt, the operator may release his hold on the plate quicker, and regular oper-

ation is insured by having projections on the surface of the conveyor which indicate the positions at which the plates are to be placed thereon with a sufficient amount of space and no more between the rear edge of one plate and the forward edge of the next succeeding plate.

Our invention, therefore, involves the combination with the cold rolls of a tin plate mill, of a power driven endless conveyor having projections spaced at regular intervals along its conveying surface, arranged in cooperative relation to the rolls so that plates placed upon the conveying surface of the conveyor are carried successively to and introduced between the rolls, whereby a substantially increased production is obtained from a stand or a series of stands of cold rolls from the manual operation of placing the plates upon the conveyor and allowing the conveyor to introduce them between the rolls as compared with the manual operation of introducing the plates successively between the rolls. And further the invention involves the method of continuously feeding the cold rolls of a tin plate mill at maximum capacity by the use of an endless conveyor such as that above described, and guiding the sheets to different parts of the rolls to equalize the wear on the rolls.

An embodiment of the invention is illustrated in the accompanying drawings, in which Fig. 1 is a plan view; Fig. 2 is a side view and Fig. 3 is a section on line 3-3 of Fig. 2.

Referring to the drawings, the conveyor consists of a built-up frame 1, which supports an endless sheet carrier 2. The frame supports a head roller 3, driven by suitable belt or chain and sprocket connection 4 from a suitable source of power, such as motor 5, carried on the frame 1. Supported on the frame 1 are also tail roller 6, idler rollers, 7, and adjustable tension rollers 8, over which the endless belt sheet carrier 2 moves. The sheet carrier 2 has a series of pins 9 on its carrier side for spacing sheets, such as 10, placed on the carrier. The frame 1 is preferably provided with an axle 11 and a pair of wheels 12, thus permitting the entire apparatus to be moved about readily and easily. The head of the conveyor is preferably provided with a pair of guides

13, to direct the sheets from the conveyor into the cold rolls. In order that the sheets may be made to enter the rolls at different points along the length of the rolls and thus prevent grooving of the rolls 16, the entire apparatus may be shifted, or the guides 13 may be mounted for movement back and forth at right angles to the travel of the conveyor.

16 An apparatus of this type may be placed in front of the entering stand of cold rolls 14, and may be braced and held in the desired position by means of suitable blocks 15. or by other means. In utilizing this apparatus, after the discharge end of the conveyor has been properly located with respect to the cold rolls, the carrier 2 is set in motion by starting the motor 5. It is only necessary to place sheets, such as 10, upon the traveling carrier between the spacing pins 9, and they will be automatically carried to the cold rolls. The carrier is preferably of sufficient length to permit the placing of sheets thereon at several places, and to permit several piles of sheets, such as 18, to be placed alongside of the carrier. The carrier may be fed from one or more points, either by hand or by other electrical, mechanical or pneumatic power, or by any combination of these means. The length of the carrier and the method of feeding thereto will, therefore, vary according to local conditions encountered. The spacing pins are a valuable aid in increasing the number of sheets fed. These pins designate arbitrary spaces on the carrier of sufficient size to receive the sheets to be fed, leaving the sheets properly spaced from each other for the most efficient continuous feeding to the cold rolls.

As will be apparent from the above description, the conveyor with the spacing pins 9 and guides 13 provides means for continuously supplying the cold rolls of sheet and tin plate mills with sheets, and this apparatus obtains a greatly increased output compared with the ordinary cold roll operation, and a decreased cost per ton for labor, power and maintenance. Otherwise stated, by utilizing an apparatus of this character, a given total output is obtained with a

smaller number of cold mills and therefore a less cost of plant.

What we claim is:—

1. The method of feeding sheet metal to cold rolls of tin mills and the like which comprises feeding a plurality of sheets edge to edge in substantially equally spaced positions in front of the cold rolls from more than one station and advancing the sheets together and at the same speed while maintaining them in substantially spaced relation to one another to cause them to engage the rolls successively and to be treated thereby.

2. The method of feeding sheet metal to cold rolls of tin mills and the like which comprises feeding a plurality of sheets edge to edge in substantially equally spaced positions in front of the cold rolls from more than one station and advancing and guiding the sheets together and at the same speed in a direction toward the center of the rolls while maintaining them in spaced relation to one another, and changing the direction of travel of the sheets adjacent to the rolls for delivering the same at desired points along the length of the rolls.

3. The method of feeding sheet metal to cold rolls which comprises feeding individual sheets from a plurality of sources onto an endless conveyor in such a way as to form on said conveyor a continuous series of regularly spaced sheets, and advancing said conveyor towards the cold rolls at such constant speed that the cold rolls are fed at maximum capacity.

4. The method of feeding sheet metal to cold rolls at maximum speed which comprises feeding individual sheets from a plurality of sources into a series of regularly spaced, approximately aligned individual sheets, continuously advancing said series at constant speed to feed the rolls, and replenishing the series as the sheets are passed through the rolls.

This specification signed this 24th day of November, 1923.
